(57) **CLAIM**

The ornamental design for a modular component for a multimedia storage tray, as shown and described.

DESCRIPTION

FIG. 1 is a perspective view of the modular component for a multimedia storage tray, incorporating the design of my new invention;

FIG. 2 is a top plan view thereof;

FIG. 3 is a bottom plan view thereof;

FIG. 4 is a front elevational view thereof, with the rear elevational view being identical thereto;

FIG. 5 is a right-side elevational view thereof; and,

FIG. 6 is a left-side elevational view thereof.
